UNITED STATES PATENT OFFICE.

MONTAGUE MCSELEY BEAR, OF ATLANTA, GEORGIA.

CLASP.

Application filed April 20, 1927. Serial No. 185,269.

The present invention relates to improvements in clasps and has for an object to provide an effective and ornamental clasp for use in connection with garters, for holding neckties and numerous other uses.

Another object of the invention resides in providing a clasp of a construction and form which will admit of its readily acquiring a monogram or other ornamentation and in which the desirable resiliency will not be sacrificed in any way.

It is a further object of the invention to provide a clasp of neat appearance, simple and inexpensive construction and one in which the parts may be readily separated and assembled.

With the foregoing and other objects in view, the invention will be more fully described hereinafter, and will be more particularly pointed out in the claims appended hereto.

In the drawings, wherein like symbols refer to like or corresponding parts throughout the several views.

Figure 1 is a plan view of a garter showing the improved clasps one of which is partly broken away.

Figure 2 is a front elevation, partly broken away, of the improved clasp on an enlarged scale.

Figure 3 is an edge view of the same in the closed position.

Figure 4 is a rear elevation.

Figure 5 is a longitudinal section taken on the line 5—5 in Figure 4, and

Figure 6 is a perspective view of the locking lever.

Referring more particularly to the drawings 7 designates an inelastic band portion of a garter to one end of which is attached the elastic webbing 8 having the length adjusting device 9 and the attaching loop 10; and to the other end of such inelastic band 7 is the tongue 11 adapted to underlie the attaching loop 10 and the attaching wedge or head 12.

The inelastic band 7 is adapted to carry one or more, preferably two pendant pads 13 and 14 preferably disposed at opposite sides of the leg for holding the two clasp members shown.

The improved clasp consists of a substantially U-shaped frame composed of the rear leg 15, the front leg 16 and the connecting yoke or loop 17. The frame is preferably of steel or some other material possessing

inherent resiliency and the legs 15 and 16 are spaced apart. At the free end portion of the leg 15 is a transverse groove 18 adapted to receive the teeth 19 of the claw 20 which lies at substantially right angles to the operating plate 21, which together with the claw constitutes the locking lever. The claw is provided with the laterally projecting trunnions or pivot pins 22 and 23 for fitting within the semi-circular bearings 24 and 25 near the free edge of the front leg 16 of the frame. These bearings 24 and 25 open inwardly and the trunnions are retained yieldably in place by the spring plate 26 which is riveted or otherwise secured to the inner face of the front legs 16, as for instance shown at 27. The rivet may be a square one in order to prevent a rocking movement of the spring plate 26.

The spring plate 26 is provided with a cut out portion 28 in registry with a similar cut out portion 29 in the front leg 16 of the frame. These cut out portions are in alignment with the claw 20 and through these cut out portions the claw is arranged to extend over and engage the inner face of the rear leg 15. The claw 20 will be of such size as to resiliently engage the rear leg 15 whereby to pry the legs apart as the claw is being forced to the right angular position across the legs, as shown in Figure 3. In its final position, as shown in this figure, the teeth 19 of the claw have snapped into the locking groove 18, and the inherent resiliency of the frame holds the claw yieldably in place with the operating plate 21 close against the outside face of the front leg 16.

This plate 21 may be produced in any ornamental shape or form, and it may be produced in any desired color or it may be gold or silver plated or oxidized. It is suitable for bearing a monogram either upright or sidewise or any desired design may be reproduced thereon.

The yoke or loop portion 17 of the frame is adapted to receive the ring 30 held by the stitching 31 to the garter pad 13. As shown by the broken away clasp in Figure 1, the rear leg 15 may also be provided with openings or eyes 32 to receive stitching for attaching the clasp to the extended portion of the pad.

The locking lever may be removed by simply turning the same at right angles to the plane of the operating plate 21 when the

plate is substantially in the open position, as shown in full lines in Figure 5. This movement will automatically pry the rounded trunnions 22 and 23 out of the semi-circular bearings 24 and 25, forcing the spring plate 26 inwardly.

The slots 28 and 29 will be elongated to permit of the trunnions and claw being slipped outwardly therethrough. This facilitates assembly and allows substitution of parts when wear occurs or when the monogram is to be changed.

Although the improved clasp has been described in connection with a garter it will be understood that it may have many other uses.

The plate 21 or other parts of the device may be made of solid gold, sterling silver, steel, brass, plated gold or silver or may be oxidized or produced from any other desired material.

The teeth of the lever may preferably be dipped in celluloid, gutta percha or some rubber solution, especially where used in connection with fine fabrics such as lingerie and handkerchiefs in order to avoid tearing or injury to same.

It is obvious that various changes and modifications may be made in the details of construction and design of the above specifically described embodiment of this invention without departing from the spirit thereof, such changes and modifications being restricted only by the scope of the following claims:—

What is claimed is:—

1. An improved clasp comprising a U-shaped resilient metallic frame having front and rear spaced parallel legs, pressed out half bearings in the front leg having open

inner sides, a locking lever having an operating plate and a claw extending angularly to the plate and provided with trunnions adapted to be received in the half bearings from the inner side of the front leg, said claw adapted to engage the rear leg and spring the same under tension away from the front leg, and a spring plate secured to the inner side of the front leg and having portions engaging over the open sides of the half bearings to confine the trunnions yieldably therein, said spring plate and front leg both having elongated and wide registering openings therein for receiving the claw and trunnions therethrough from the outer side of the front wall.

2. An improved clasp comprising a U-shaped resilient metallic frame having front and rear spaced parallel legs, pressed out half bearings in the front leg having open inner sides, a locking lever having an operating plate and a claw extending angularly to the plate and provided with trunnions adapted to be received in the half bearings from the inner side of the front leg, said claw adapted to engage the rear leg and spring the same under tension away from the front leg, and a spring plate secured to the inner side of the front leg and having portions engaging over the open sides of the half bearings to confine the trunnions yieldably therein, means for attaching said spring plate to the front leg remote from said half bearings, said spring plate and front leg having registering openings of substantial length and width to receive therethrough the claw and trunnions when turned sidewise, whereby to permit of detachable attachment of the claws and levers.

MONTAGUE MOSELEY BEAR.
